SERVING TRAY

Charles Kolacy, Bloomfield, N. J.

Application March 7, 1946, Serial No. 652,496

3 Claims. (Cl. 65—53)

1

This invention relates to trays and in particular to trays adapted for household use in the serving of drinks and edibles.

A particular object of the invention is to provide a tray structure in which a sinuous strip is used, the convolutions of which form glass holding compartments, said strip being removably positioned in the ends of the tray and being readily detachable therefrom for the purpose of cleaning.

A still further object of the invention is to provide one or more flexible partition strips for use in combination with the sinuous strip so that the tray may be partitioned to present different ornamental effects.

Other important objects of the invention are the construction of a tray, the body portion of which may be made of grooved strips in which may be secured the tray bottom, the parts being held together by a handle at each end and the parts of the tray as well as the attachments being made of plastic, metal, wood, Lucite, or combinations of any of these; to provide attachments for the tray that can be sold separately to be attached to trays already in use or on the market and to provide a tray structure which is easily cleaned and from which all of the attachments may be removed in order that the tray may be maintained in a sanitary condition.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a view in perspective of a serving tray constructed in accordance with my invention.

Fig. 2 is a plan view of a sinuous strip used in opposite ends of a tray and constituting a glass holder.

Fig. 3 is a plan view of a partition strip, one or more of which may be used with the glass holding strips.

Fig. 4 is an enlarged section taken on the line 4—4 of Fig. 1 showing the relative arrangement of the parts at one end of the tray.

Fig. 5 is a plan view of one end of a tray showing a modified arrangement of the glass holding strips and one of the partition strips.

Fig. 6 is a fragmentary plan view of a corner of a tray showing a modified use of one of the partition strips.

Referring to the drawing in detail 10 indi-

2

cates a tray which may be employed for the general purpose of serving drinks and other items of food and having sides 11 which may be constructed of plastic or other suitable material, grooved as at 12, see Fig. 4, about the inside face thereof to provide a channel in which the edges of a bottom 13 may be seated. As illustrated in Fig. 1, the sides 11 of the tray may be made substantially U-shaped so that when they are brought together to form a rectangle and support the bottom 13 therebetween, they may be held together by the handles 14 secured to the ends of the sides 11 as by the screws or other holding means 15.

15 The tray may be of any shape desired and is rounded at its corners as at 16 to provide a pleasing contour, the bottom of the tray being ornamented as at 17, if desired, to provide a decorative effect. In this particular form of the invention, the sides 11 are made of Lucite and the bottom 13 is made of glass, it being understood that any combination of materials may be employed that will serve the purpose.

17 The tray 10 is arranged to have placed in the opposite ends thereof, glass holding members 18 which are both made the same and simply reserved for use at the opposite ends of the tray. The glass holding members 18 are made from a sinuous strip of flexible material such as plastic, Lucite, or the like, which is shaped to provide convolutions 20 joined by the loops 21, the latter of which abut the ends 22 of the tray while the ends of the strip engage the sides of the tray with sufficient force to maintain the glass holding strip in place. It will be understood that when the strip 18 is formed its convolutions will provide a resilient or spring effect so that it may be longitudinally compressed to be frictionally seated in the tray.

20 In order to divide the tray into suitable compartments for nuts, candy or the like, use is made of one or more flexible partition strips 23, the ends of which are curved as at 24 to fit the contour of the convolutions 20 of the sinuous strips 18. As illustrated in Fig. 1, the use of two of the strips 23 will provide a large center compartment and four smaller corner compartments while the glass holding strips will provide receptacles for eight glasses. In Fig. 3, the flexibility of the partition strip 23 is illustrated in outline and in the use of two of the strips, it is simply necessary to make both alike and reversely position one to obtain the effect illustrated in Fig. 1.

25 In the form of the invention illustrated in Fig. 5, use is made of the glass holding strips 18

in the rounded ends 25 of a tray 10, showing the adaptability of the strips 18 to trays having different shapes. In this form of the invention one of the strips 23 is looped so that its opposite ends are held between the convolutions 20 of the same strip 18. This looped form of the strip 23 will provide a different ornamental effect and shows the adaptable nature of the interchangeable plastic attachments that I provide in connection with the tray.

In Fig. 6, I have shown the use of a single strip 23 that may be positioned between the first and second convolutions 20 of the glass holding strip 18 to provide a different tray effect, it being evident that another such strip 23 may be used at the opposite side of the tray engaging the first loop 20 of the glass holding strip 18. The flexibility of the strip 18 and the separation of the convolutions 20 thereof to accommodate the ends of the strips 23 are made possible by the loops 21 that join the convolutions 20.

It is evident therefore, that I have provided a tray the structure of which is sufficiently simple to permit manufacturing assembly at reduced cost and by the use of a minimum number of parts to make up the completed tray, which parts may be made in duplicate and may be interchangeably used to provide different ornamental effects for the tray.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with an elongated serving tray having a bottom wall, side walls and end walls, a sinuous strip of flexible material positioned in each end of the tray and resting on the bottom wall thereof, each of said strips having a plurality of convolutions connected by loop portions, said looped portions of said strips facing with their open sides directed toward the open side of the other, and a pair of flexible partition strips having their ends engaging longitudinally aligned loop portions of said sinuous strips.

2. In a combination with an elongated serving tray having a bottom wall, side walls and end walls, a sinuous strip of flexible material positioned in each end of the tray and resting on the bottom wall thereof, each of said strips having a plurality of convolutions connected by loop portions, said looped portions of said strips facing with their open sides directed toward the open side of the other, and a pair of flexible partition strips having their ends engaging longitudinally aligned loop portions of said sinuous strips, said flexible partition strips being of a length greater than the length of the tray to have their ends engage the aligned loop por-

tions at opposite ends of the tray with the intermediate portions of the partition strips bowed away from each other to engage the inner faces of the side walls of the tray retaining the sinuous strips in engagement with the inner faces of the end walls of the tray.

3. In combination with an elongated serving tray having a bottom wall, side walls and end walls, a sinuous strip of flexible material positioned in each end of the tray and resting on the bottom wall thereof, each of said strips having a plurality of convolutions connected by loop portions, said looped portions of said strips facing with their open sides directed toward the open side of the other, and a pair of flexible partition strips having their ends engaging longitudinally aligned loop portions of said sinuous strips, said flexible partition strips being of a length greater than the length of the tray to have their ends engage the aligned loop portions at opposite ends of the tray with the intermediate portions of the partition strips bowed away from each other to engage the inner faces of the side walls of the tray retaining the sinuous strips in engagement with the inner faces of the end walls of the tray, said flexible partition strips having their adjacent end portions curved away from each other to follow the contour of the adjacent convolutions of the sinuous strips between which the end portions of the partition strips are engaged to hold the flexible partition strips against movement relative to the sinuous strips.

CHARLES KOLACY.
